UNITED STATES PATENT OFFICE.

CHARLES M. TERRY, OF DECATUR, ILLINOIS, ASSIGNOR TO A. W. CASH COMPANY,
OF DECATUR, ILLINOIS, A CORPORATION OF DELAWARE.

AUTOMATIC REGULATING MEANS.

Application filed March 26, 1925. Serial No. 18,352.

To all whom it may concern:

Be it known that I, CHARLES M. TERRY, a citizen of the United States, residing at Decatur, in the county of Macon and State of Illinois, have invented certain new and useful Improvements in Automatic Regulating Means, of which the following is a specification.

My invention relates to automatic regulating means, responsive to pressure variations, for controlling adjuncts (such as blast or stack dampers, fan or stoker feed drive mechanism, etc.) of a steam boiler furnace equipment or the like to maintain the desired operating conditions, and more particularly has to do with the valving device for controlling the position of the piston structure of the fluid operated motor under the control of the pressure responsive element of the apparatus. The main object of my invention is to so form the escape ports of the valve device that they direct the jets or streams of motive fluid in such directions that they do not interfere with the operation of the valve and do not cause leakage in the wrong direction through or past the valve member for controlling the extent of opening of the ports.

In the accompanying drawings I have shown my invention applied to the type of regulator shown and described in my co-pending application Serial No. 707,314, filed April 17, 1924, to which my present invention is peculiarly adapted for application, although it will be evident that the invention may be used in other kinds and types of regulators and therefore I do not intend to limit the use of the invention to the particular type of regulator disclosed herein.

In said drawings, Figure 1 is a vertical cross-section through my improved regulator, and Fig. 2 is an enlarged detail taken through part of the piston structure and the sleeve or engine valve.

Referring to Fig. 1, one end of a cable 5 is connected to the top of a piston rod 6, which is of tubular construction, and open at its lower end through the piston 7 of the hydraulic or fluid operated motor. For the sake of illustration, I have diagrammatically shown, on a very reduced scale, the cable as running over suitable guide pulleys and

connected at its opposite end to a segment 9, which carries a weight 10 and to which is connected a damper 11 in a stack of the 55 furnace to be controlled. The piston 7 tends constantly to rise to the top of its cylinder 13 under the pull of the damper weight 10, but water or other motive fluid under pressure flows in a small steady stream into the 60 upper end of the cylinder 13 through a constantly open port from a pipe 12 and the fluid pressure is employed to overcome or balance the effect of the damper weight 10. The liquid thus introduced above the piston 7 can escape from the cylinder 25 through my improved valve controlled ports 14, preferably four in number, formed in the hollow piston rod 6 and controlled by a slide valve 15 mounted within the piston rod. 70 This valve 15 is in the form of a tube or sleeve, the lower end portion being adapted to open ports 14 more or less. A pin 17, extending through the valve, supports a connecting block 18. The bottom of this 75 block is connected by a flexible member 19, preferably, a ball-chain, with a float 20 positioned in a casing 21. The upper end of the block 18 is preferably connected by a ball-chain 22 and a suitable stirrup with 80 a valve-opening lever 23 carrying a weight 24 which constantly tends to open the valve 15. The lever 23 is suitably pivoted on a bearing head carried by the piston rod and one end of the lever passes through suitable 85 slots 24' in the piston rod to permit movement of this lever about its pivot. I also connect to the lever 23 a variable weight 26, which is in the form of a chain, as shown. 90

The motor cylinder 13 is mounted centrally upon the casing 21 and the base 28 of the motor casing forms the upper head of the casing 21 and has a central opening 27 through which the ball-chain 19 passes. The 95 water that escapes from the upper end of the motor through the ports 14 is led through a duct 29 in the base 28 into the float chamber formed by the casing 21.

A pressure communicating pipe 30 opens 100 at one end (not shown) into the combustion space of the furnace and at its other end into the bottom of the casing 21, and has its vertical pipe-extension 30', within the

casing 21, opening into the hollow float 20. On the bottom of the casing 21 I provide the central overflow tube or kerb 32 through which the overflow takes place, the overflow 5 draining through the drain pipe 31.

In operation, the hydraulic motor normally stands in balanced pressure condition, with its piston at such point that the lower portions of the ports 14 are just sufficiently 10 opened by the valve 15 to permit the steady escape of water, through these ports down through the duct 29 into the float chamber, equal to the constant inflow through the pipe 12. Any rise of pressure in the combustion 15 space of the furnace is communicated to the interior of the float 20 through the pipe 30 and its extension 30' and raises the float to some degree. The weight 24, through the lever 23 and chain 22, raises the valve 15 up higher in the piston rod, so 20 opening wider the ports 14. This relieves the water pressure in the top of the motor cylinder and so the damper weight 10 raises the piston rod up around the float-restrained 25 valve 15 until the ports 14 are sufficiently throttled to restore the balancing pressure. Should the pressure in the furnace drop, the reverse action takes place, as the float 20 sinks to a corresponding extent, dragging 30 down the valve 15, which momentarily diminishes the effective opening of the ports 14, whereupon the water pressure promptly builds up in the cylinder to force the piston down until adequate port opening is again 35 established.

It will now be noted that I have formed the lower ends of the slotted ports 14 so that they incline inwardly and downwardly. This construction has very decided advantages 40 as it directs the jets of water downwardly, as indicated diagrammatically by the lines 33 in Fig. 2, away from the lower end of the valve 15 and at an inclination toward the lower end of the connecting block 45 18. Were the lower ends of the ports 14 horizontal, the jets of water would be directed horizontally into the piston rod and at right angles to the connecting block and with such arrangement, I find that when 50 the water above the piston 7 is under high cylinder pressure and consequently is passing at high velocity through the relief ports 14, the water strikes the block and the streams of water are divided, part of the 55 water being forced up through the hollow valve and the piston rod and out of the slots 24' by the velocity head, and such action is obviously objectionable and to some degree impairs the efficiency of the device. 60 With the improvement embodying my invention these objections are entirely avoided and eliminated as the jets are directed downwardly.

I claim:

65 1. In a regulating device of the class de-

scribed, the combination of a hydraulic motor, having a piston with a hollow piston rod provided with ports, a valve slideable in said piston for controlling said ports, the ports being formed to direct the streams of liquid flowing through said ports at an inclination away from said valve, and a pressure responsive member controlling the operation of said valve.

2. In a regulating device of the class described, the combination of a hydraulic motor having a piston with a hollow piston rod, a sleeve valve slideable in said piston rod for controlling said ports, a pressure responsive device and connections between said valve and said pressure responsive device including a flexible element, said ports in said piston rod being formed to direct the jets of liquid flowing through said ports at an inclined angle and away from said valve.

3. In a regulator of the class described, the combination of a pressure responsive device, a hydraulic motor having a piston structure, a valve carried by the piston structure, a connection between said valve and said device, said motor having a fluid supply connection to one side only of said piston, and a fluid outlet port through said piston structure and controlled by the valve, the port having an inclined side to direct the jet of liquid flowing through said port at an inclined angle and away from said valve.

4. In a regulating device of the class described, the combination of a pressure responsive device, a hydraulic motor having a piston structure and a sleeve valve carried by the piston structure, a connecting block secured to said valve, a chain connected to said block and to said device, said motor having a fluid supply connection to one side only of said piston, and a fluid outlet port formed in said piston structure and controlled by said valve, the port having its lower side inclined to direct the jet of liquid flowing through said port at an inclination toward said block and away from said valve.

5. In a regulating device of the class described, the combination of a valve structure, including a valve and a hollow member in which the valve slides and through which liquid escapes, a pressure responsive element for controlling the operation of said valve, and a flexible connection between said element and valve, said hollow member having ports controlled by said valve and through which jets of liquid pass into said hollow member, the ports being formed to direct the jets at an inclined angle with respect to said flexible connection and away from said valve.

6. In a regulating device of the class described, the combination of a valve structure including a sleeve valve and a hollow

member in which the valve slides, a pressure responsive element for controlling the operation of said valve, and a flexible connection including a chain between said element and valve, said member having a port which is controlled by said sleeve valve, and through which a jet of liquid passes into

said hollow member, the port having its side, uncovered by the valve, inclined to direct the jet of liquid at an inclination with ¹⁰ respect to said chain and away from the end of said valve.

CHARLES M. TERRY.
